The dominant features of our design are shown in full lines.

The distinctive characteristic of the design is the parting line in each end wall which extends between the body and hinged cover diagonally of the respective wall and terminates short of the bottom wall, each said parting line having a relatively short merging portion adjacent to the top of the case substantially parallel with the back wall thereof, and its terminus adjacent to said hinge being offset rearwardly of the front wall of the case and being connected with said front wall by a portion substantially normal to the diagonal of said parting line.

We claim:
